REVOLVER CYLINDER

Adam Mesko, China Lake, Calif.

Application May 6, 1957, Serial No. 46,027

Term of patent 14 years

(Cl. D30—1)

Fig. 1

Fig. 2

Fig. 3

Figs. 1 and 2 are side elevations of a revolver cylinder, as viewed from opposite sides, respectively, showing my new design;

Fig. 3 is an enlarged fragmentary detailed view taken of the right end of the side elevation shown in Fig. 1.

I claim:

The ornamental design for a revolver cylinder, as shown.
